UNITED STATES PATENT OFFICE.

POVL T. LINDHARD, OF BROOKLYN, NEW YORK, ASSIGNOR TO F. L. SMIDTH & CO., OF NEW YORK, N. Y., A CORPORATION OF NEW JERSEY.

GRINDING MILL.

Application filed June 28, 1922. Serial No. 571,385.

to all whom it may concern:

Be it known that I, Povl T. LINDHARD, a citizen of the United States, residing in the borough of Brooklyn, in the city and State of New York, have invented certain new and useful Improvements in Grinding Mills, of which the following is a specification, reference being had to the accompanying drawings, forming a part hereof.

10 In Letters Patent of the United States No. 1,437,599, dated December 5, 1922, there are shown and described certain improvements in grinding mills which are concerned more particularly with the provision of relatively great screening surface or area within a comparatively restricted space. The present invention is concerned with the construction of the separators or screening devices and with the general internal construction of a grinding mill in which a screening or separating compartment is interposed between two grinding compartments and in which provision is made for the grinding within the screening or separating compartment of the tailings which are retained therein as the finely ground material is separated from such tailings. The invention will be explained more fully hereinafter with reference to the accompanying drawings in which—

Figure 1 is a view in longitudinal, central section, of the improved grinding mill.

Figures 2 and 3 are detail views, in longitudinal section and transverse section respectively, and on a larger scale than that of Figure 1, illustrating one form of construction of the screening devices.

Figures 4 and 5 are views generally similar to Figures 2 and 3 but illustrating a slightly different form of construction.

Figures 6 and 7 and Figures 8 and 9 are detail views on a still larger scale, illustrating two other forms of construction.

In the embodiment of the invention illustrated in Figure 1, a generally cylindrical shell *a*, of usual construction except as hereinafter indicated, mounted and rotated in usual manner, is provided at one end with an inlet or feed head *c* and at the other end with an outlet or discharge head *d*. It is shown as comprising a primary grinding chamber *e*, provided in the usual manner with grinding bodies *e'* and a lining *e''*,

a secondary grinding chamber *f*, also provided with grinding bodies *f'* and a lining *f''*, and an intermediate screening or separating compartment *g*. A lifting partition *h*, of the usual construction, having the usual radial vanes or ribs *h'*, by which the material is lifted, and the usual cone *h''* by which the material discharged by the vanes is directed through the central opening in the second wall into the succeeding compartment, interposed between the primary grinding compartment *e* and the separating compartment *g*, is arranged to deliver from the primary grinding compartment *e* into the separating compartment the material which has been partly ground in the primary grinding compartment *e*. A lifting partition *h'*, also of ordinary construction, is disposed between the separating compartment *g* and the secondary grinding compartment *f*, and is arranged in usual manner to deliver the material, which has already been partly reduced in the compartment *e* and separated in the compartment *g* from the tailings, into the secondary grinding compartment *f* where it receives a further grinding.

The grinding compartment *g* is provided with one or more screens or separators *n* which may be constructed as hereinafter described, although not necessarily so, and with an inner shell *g*, of smaller diameter than the shell *a* so that there is formed, between the two shells *a* receiving and conveying space *o*, which may be fitted with spiral conveyors *o'*, by which the partially reduced material which is separated, in the separating chamber, from the tailings, is passed on to the secondary grinding compartment. In order that the reduction of the tailings in the separating compartment may be continued, the separating compartment is provided with a lining *g''* and with grinding bodies *g'*.

So far as the general construction and arrangement of the grinding mill are concerned, the precise construction of the separating devices is immaterial, but in order that both the primary and the secondary grinding may be accomplished in the one shell, with effective separation of the finer material from the coarse material, without undue expansion of the separating compart-

ment between the two grinding compartments, it is desirable to provide separating devices of the general character of those described in said application and it is preferable that the separating devices be constructed substantially as will now be described.

In the construction shown in Figures 2 and 3 the separating compartment g is shown as provided with two screens or separators, each of which is annular, surrounding an open center, and is made up of a series of cages n^2 , each of which is made up of a frame n^{21} and two members n^3 , perforated as at n^4 , the cage members being secured in place by bolts n^5 , which pass through the lining g^2 of the shell g' , bearing blocks o^2 and the outer shell a . The members n^3 of each cage may be further secured together by bolts n^6 . Each separator unit or cage n^2 has a free opening between its members n^3 , adjacent the shell g' , which registers with an opening g^4 through the lining and the inner shell so that the finer material, which passes through the perforated side walls of the separator units, shall pass freely into the receiving and conveying space o , between the shells a and g' , and be caused by the conveyer o' to pass onward until it reaches the lifting partition h' and is thereby transferred to the secondary grinding compartment f .

In the construction of the separating devices shown in Figures 4 and 5, the separator units n^2 are formed as already described with respect to Figures 2 and 3. The inner shell g^5 is shown as having the conveyor plates o^3 formed integrally therewith and bearing directly against the outer shell a . In this instance the bearing blocks are dispensed with, the bolts n^5 passing through the inner shell g^5 and the outer shell a . Openings g^4 are formed in the shell g^5 , as previously described, to permit the finer material to pass from between the perforated side walls of the separator units into the receiving and conveying space o between the two shells, through which it is conveyed, as before, to the lifting partition h' by which it is transferred to the secondary grinding compartment f , while the tailings, retained within the separating compartment, are further reduced by the grinding bodies g^3 with which the separating compartment is charged.

In the construction shown in Figures 6 and 7 each separating unit n^7 , having perforated side walls as before, is shown as formed as a single casting provided with notched flanges n^8 , for engagement by bolts n^9 , which are in turn engaged with a flanged frame n^{10} , riveted, as indicated at n^{11} , to the inner shell g' around the opening g^6 , through which the separator unit is passed from the outside of the shell. In this construction the finer material, which passes

through the perforated walls of the separator unit, passes into the space o between the inner and outer shells and then is transferred as previously described, to the lifting partition h' , by which it is transferred to the secondary grinding compartment f .

The construction illustrated in Figures 8 and 9 is substantially like that illustrated in Figures 6 and 7, except that each separator unit n^{12} is passed from the outside of the shell a through an opening a' therein and through an opening g^7 in the shell g' , the separator unit having open ends, as at n^{13} , through which the finer material escapes into the space o between the inner and outer shells. In this instance the separator unit has a notched flange n^{14} for engagement with bolts n^{15} which are in turn engaged with a notched and flanged frame n^{16} , secured by riveting or otherwise to the shell a around the opening a' .

Various other forms of separating devices, suitable for use in a mill of the character of that indicated herein, will readily suggest themselves and it will be understood, that except as pointed out in the claims, the invention is not restricted to the particular construction shown and described herein.

I claim as my invention:

1. A grinding mill comprising a rotatable shell, two lifting partition disposed in the shell and forming a primary grinding compartment, a secondary grinding compartment and an interposed separating compartment, said separating compartment having an inner shell separated from the first mentioned shell to form a receiving and conveying space between the two, the inner shell having openings therethrough, and a separating device disposed in the separating compartment and arranged to deliver the finer material through the opening in the inner shell into the receiving and conveying space between the two shells.

2. In a grinding mill, the combination of an outer shell, an inner shell separated from the outer shell to form a receiving and conveying space and having an opening therethrough and a separating cage secured in position with its open end in registration with the opening through the inner shell.

3. In a grinding mill the combination of an outer shell, an inner shell separated from the outer shell to form a receiving and conveying space and having openings therethrough and an annular series of separating cages secured in position with their open ends in registration with the openings through the inner shell.

4. In a grinding mill the combination of an outer imperforate shell, an inner shell having an opening therethrough, a separator cage having opposite perforated walls with a free opening between them for registration with the opening through the shell,

and means to secure the cage in position in relation to the shell.

5. In a grinding mill the combination of an outer imperforate shell, an inner shell 5 having openings therethrough, an annular series of separator cages having opposite perforated walls with free openings between

the walls for registration with the openings through the shell, and means to secure the separator cages in relation to the shell. 10

This specification signed this 17th day of June, A. D. 1922.

POVL T. LINDHARD.
